(57) **CLAIM**

The ornamental design of a hinged bird guard for a dryer vent, as shown and described.

DESCRIPTION

FIG. 1 is a front isometric view of a hinged bird guard for a dryer vent with the hinged bird guard in a closed position; FIG. 2 is a rear isometric view thereof with the hinged bird guard in the closed position;

FIG. 3 is a front plan view thereof with the hinged bird guard in the closed position;

FIG. 4 is a rear plan view thereof with the hinged bird guard in the closed position;

FIG. 5 is a left-side plan view thereof with the hinged bird guard in the closed position;

FIG. 6 is a right-side plan view thereof with the hinged bird guard in the closed position;

FIG. 7 is a top plan view thereof with the hinged bird guard in the closed position;

FIG. 8 is a bottom plan view thereof with the hinged bird guard in the closed position;

FIG. 9 is a rear isometric view thereof with the hinged bird guard in an open position;

FIG. 10 is a front isometric view thereof with the hinged bird guard in the open position;

FIG. 11 is a rear plan view thereof with the hinged bird guard in the open position;

FIG. 12 is a front plan view thereof with the hinged bird guard in the open position;

FIG. 13 is a left-side plan view thereof with the hinged bird guard in the open position;

FIG. 14 is a right-side plan view thereof with the hinged bird guard in the open position;

FIG. 15 is a bottom isometric view thereof with the hinged bird guard in the open position; and,

FIG. 16 is a top isometric view thereof with the hinged bird guard in the open position.

The broken lines depict portions of the hinged bird guard for a dryer vent that form no part of the claimed design.

1 Claim, 8 Drawing Sheets
